(57) **CLAIM**

The ornamental design for a flask, as shown and described.

DESCRIPTION

A portion of the disclosure of this patent document, including appendices, may contain material which is subject to copyright protection. The copyright owner has no objection to the facsimile reproduction by anyone of the patent document or the patent disclosure, as it appears in the Patent and Trademark Office patent filed or records, but otherwise reserves all copyright rights whatsoever.

FIG. 1 is a perspective view of the flask showing the new design;

FIG. 2 is a top plan view thereof;

FIG. 3 is a bottom plan view thereof;

FIG. 4 is a side elevational view thereof; and,

FIG. 5 is an exploded perspective view showing the internal components of the flask.
